Application March 18, 1953, Serial No. 24,098

Term of patent 14 years

(Cl. D10—8)

To all whom it may concern:

Be it known that we, Earl M. Borchers and Axel W. Ahlgren, citizens of the United States, residing at Rockford, in the county of Winnebago and State of Illinois, have invented a new, original, and ornamental Design for a Surface Mount Door Catch, of which the following is a specification, reference being had to the accompanying drawing, forming a part thereof, wherein:

Fig. 1 is a top plan view of a surface mount door catch showing our new design.

Fig. 2 is an end elevational view of the catch shown in Fig. 1.

Fig. 3 is an elevational view of the portion of the catch shown on the right in Fig. 2.

Fig. 4 is an elevational view of the portion of the catch shown on the left in Fig. 2.

The dominant features of the design reside in the portions illustrated in full lines.

We claim:

The ornamental design for a surface mount door catch, as shown and described.

EARL M. BORCHERS.
AXEL W. AHLGREN.
